UNITED STATES PATENT OFFICE.

HENRY M. CRIPPEN, OF ATHENS, OHIO, ASSIGNOR TO THE ATHENS BINDERY COMPANY, A FIRM COMPOSED OF HENRY M. CRIPPEN, WILLIAM N. ALDERMAN, FIELD SCOTT, AND H. H. HANING.

LOOSE-LEAF-BINDING MACHINE.

1,346,179.

Specification of Letters Patent. Patented July 13, 1920.

Application filed October 14, 1919. Serial No. 330,573.

To all whom it may concern:

Be it known that I, HENRY M. CRIPPEN, a citizen of the United States, residing at Athens, in the county of Athens and State of Ohio, have invented certain new and useful Improvements in Loose-Leaf-Binding Machines, of which the following is a specification.

My invention relates to certain improvements in the loose leaf binding machine shown in my Patent 1,255,112, January 29, 1918.

The objects of the invention are to provide the crosshead carrying the punches with an automatically actuating stripper or ejector which will when said punches are brought into register with the sheet-receiving pins transfer the sheets thereto; also to provide interchangeable sets of receiving pins for different sizes of sheets; to provide novel means for removably securing such sets of receiving pins in place; to provide a novel means for holding the sheet clamp in place upon a pile of sheets; also to improve the sheet carrier by making it movable vertically at both ends so as to better raise the pile of sheets from the receiving pins; also to form the sheet carrier in hinged sections so that its inner end may be withdrawn from over the base of the set of receiving pins to permit of the removal and replacement of said pins; to provide clamping hooks to hold down the pile of sheets in the upward movement of the sheet carrier; also to provide the hollow anvil with a removable drawer to receive the punchings; also to provide other novel and useful features as will be fully pointed out hereinafter.

These objects I accomplish by the construction shown in the accompanying drawings, in which:

Figure 1 is a sectional perspective of the machine with the parts in position for punching a pile of sheets, the filing pins being removed.

Fig. 2 is a plan thereof.

Fig. 3 is a side elevation thereof partly in section.

Fig. 4 is a longitudinal section on line 4-4, Fig. 2.

Fig. 5 is a cross section similar to Fig. 4 with the punching head over the pins.

Fig. 6 is a similar view, showing the

stripper forced down upon a pile of sheets impaled on the pins. 55

Fig. 7 is a similar view with the punching mechanism thrown to the left and the clamp held down on a pile of sheets as the sheet carrier is being elevated.

Fig. 8 shows a transverse section on line 8-8, Fig. 7.

Fig. 9 is a detail perspective, showing the removable pins about to be placed on the axle.

Fig. 10 is a bottom plan view of the sheet 65 and clamp carrier.

Figs. 11 and 12 are detail sections of the slotted inner end of the sheet and clamp carrier and adjacent underlying parts.

Fig. 13 is a perspective of the removable 70 drawer for the punchings.

Fig. 14 is a detail, showing several ways of securing the sheets together.

Fig. 15 is a perspective of a set of filing pins having a less number of pins than in 75 Fig. 9.

The bed or frame A may be of any suitable construction and as illustrated is in oblong form with the side bars A' A' connected at the right by an end bar A² and 80 connected near their left hand ends by a metal crossbar A³ upon which is mounted the horizontal gage flange g² of the tubular anvil housing G, provided with a longitudinal slot g, with which registers any one of 85 a series of apertures h in the tubular anvil H, as shown in my said Patent 1,255,112. Instead of the end caps h' of said patent I provide the sliding drawer H' which closely fits the interior of the anvil H and has an 90 opening h' to receive the punchings from the anvil openings h. The drawer H' may be readily removed to discharge the punchings.

Extending inwardly from the ends of the 95 anvil housing G are two horizontal arms g³ mounted at their inner ends on an axle E, the ends of which are fixedly secured in the side bars A' by pins e'. The ends of the axle E extend beyond the side bars and are provided with heads e e for a purpose hereininafter described. The inner ends of the arms g³ are provided on their upper sides with stops g⁴ and the ends of the anvil housing are provided with stops g'. 100

From the gage plate g² on the anvil hous-

ing G extends the curved sheet guide F, provided with slots f and secured at the lower edge of its inner vertical wall F' to the axle E, as in said patent. At the ends of the sheet guide F are braces F² provided at their inner ends with laterally extending hooked stops f² above the stops g⁴.

The axle E is formed with an angular upper edge e⁶, preferably inverted V shape, and is further provided with a series of vertical apertures e⁷ into which extend the lower ends of a series of sheet-receiving pins J extending vertically from an angle shape bar J' resting removably on the axle E; the upper ends of the pins J terminating at the upper inner ends of the slots f. I provide a series of these bars J', each having a different number of pins J to provide for sheets of varying width so that sheets of a certain width may be applied to one set of pins and then by removing this set with the attached sheets another set may be applied. The sets of pins may be changed readily whenever necessary to file a lot of sheets of a different width without removing the sheets on the pins and permit them to be at all times visible.

Two latch hooks E⁵ E⁶ are mounted to rock on axle E and hook over the ends of bars J' to hold them in place on the axle E. These pin holding latches E⁵ are provided with extensions E⁶ E⁶ extending inwardly under the axle E adjacent to the downward path of the legs p p of clamp P when the latter is in clamping position on a pile of sheets and so prevent the latches E⁵ from swinging off of the bar J, as will be further described. The two latches E⁵ are connected by a contractile spring e¹⁰ which draws them inwardly against the ends of the inverted V shaped portions of the axle E and holds them frictionally against accidental rotation.

This feature of the interchangeable sets of pins is not found in my patent referred to and is a valuable addition, as a number of different sizes of sheets may be filed without having to remove the sheets from the pins until all of the pins of a set are filled.

K K are two swinging guide rods mounted at their inner ends on axle E and limited in their upward inward movement by the stops g⁴ at the inner ends of arms g³ and the stops f², at the ends of the member F² on the sheet guide F. The outer ends of guide rods K K are connected by a sliding crosshead K', carrying a series of punches K² to coöperate with the anvil H to punch the sheets and then carry the punched sheets up over the slotted guide F to the pins J as in my said patent.

L is a stripper or ejector bar at the inner side of the crosshead K' and apertured for the punches to pass through. This stripper L is provided with two pins l l, sliding in

apertures in the crosshead K' and provided with springs l' l' which holds the stripper against the crosshead. The crosshead K' is further provided with a hand hold k¹⁵, which serves for lifting the machine when 70 punches are in anvil.

Instead of actuating the ejector or stripper L separately by hand as in my said patent I provide for its automatic actuation in stripping the sheets from the 75 punches when the latter are in vertical alinement with pins J, as will presently appear.

The ends of the stripper L are provided with operating arms L' having T shaped inner ends carrying guide rollers l⁴ l⁴ at 80 the inner sides of their lower ends to travel along the outer sides of the guide rods K K, and said T-shaped ends are further provided at the outer sides of their upper ends with actuating rollers l³ l³, against which 85 the two lever arms M M work to depress the stripper when the punches have brought the sheets over pins J.

The crosshead K' is reciprocated on its guide rods K by means of the two links N N 90 pivoted at one end to the ends of the crosshead and at the other ends n n to the inner ends or hubs of the lever arms M M to one side of the axes thereof as in said patent.

The guide rods K K rest in their lowered 95 position on the stops g' and when swung up to the vertical they rest against stops g⁴ f².

It will be seen, therefore, that when the parts are in the positions shown in Figs. 1 100 and 2, where the guide rods K K lie horizontally and the punches are in line with the anvil apertures, that a downward movement of the lever arms M M will cause an inward movement of the links N N, which 105 in turn will force the crosshead K' and the punches K² toward the anvil H, so that a pile of sheets resting on ledge g² will be perforated. A reverse movement of the lever arms M M will move the punches out 110 of the anvil, but the sheets will remain on the punches and so by continuing the upward movement of the lever arms they will, through the rollers l³ l⁴, raise the guide rods K K and crosshead so that the sheets will be 115 carried by the punches up over the pins J and the crosshead will be stopped in this position by the stops f² g⁴. By now continuing the movement of the lever arms M M to the right their inner edges will now 120 bear down on the rollers l³ l³ of the stripper arms L' and so depress the stripper L along the punches and force the leaves downwardly off of the punches and upon the pins J.

By now raising the lever arms M M and swinging them to the left the parts may be brought, through the pulling action of the links N N and weight of the crosshead and the guide rods, into position for another 130

punching operation. This operation may be continued from time to time till the pins are filled with leaves, when the leaves may be bound to form a book, as will now be described.

- A vertically swinging sheet and clamp carrier O is pivoted at its outer or right hand end between the two side bars of the frame, but not as in my said patent. The sheet and clamp carrier is formed in two sections O' O², hinged together at the lower sides of their abutting ends, as at O², and the shorter outer section O₂ is provided on its under side at the outer edge thereof with an angle bar o, the ends of which are pivoted, as at o', to the vertical slides o³ working in guide grooves or ways o⁴ in the side bars A' A'; the upper ends of these slides o³ being provided with laterally projecting stops o⁵ to rest on top of the side bars and limit the downward movement of the slides and that end of the clamp carrier pivoted thereto. The lower ends of the slides o³ are connected by a cross-bar o⁶, engaged by the curved ends of angle levers o⁷, pivoted at their angles, as at o⁸, to the inner sides of side bars A'. From the inner arms of these angle levers o⁷ extend links o⁹, the inner ends of which are eccentrically connected to the cam-like hubs m⁵ of the levers M M. From these hubs extend the lifting cams M⁵ for a purpose to be presently described. The inner edge of the clamp carrier O has a slotted metal plate o¹⁰ to straddle the pins J, and also overlie the base J', to which the pins are secured so as to assist in holding the base J' down upon the axle. The outer shorter section O² has a handle O⁷ to swing it upwardly on its pivot and in so doing move the longer section O' to the right to cause its slotted end o¹⁰ to be withdrawn from over the pin base J', to permit the removal and insertion of the interchangeable sets of pins.
- When the two sections O' O² are moved into alignment they will be locked together so as to move as one piece vertically by means of a latch O¹⁰ of angle form pivoted at its angle, as shown at o¹², to the upper side of section O² and having a notch o¹³ adapted to engage a headed stud o¹⁴ on section O' of clamp carrier O. A retractile spring o¹⁵ tends to hold the latch in engagement with said stud o¹⁴.
- The long arm o¹⁶ of latch O¹⁰ has two notches or recesses o¹⁷ o¹⁸ in its inner edge and terminates in rear thereof in a curved extension o¹⁹ having an upwardly extending thumb piece o²⁰.
- The latch O¹⁰ is normally held in its open position by means of a transversely rocking handle bar t' extending upwardly between the two sections O' O² and connected at its lower end to the right hand end of a central longitudinal rock shaft T mounted in bear-

ings on the lower side of section O' of the clamp and sheet carrier O. The inner end of the rock shaft T has a vertically disposed head t lying between the two depending lugs r r of two transverse slides R R mounted in 70 bearings r' r' on the under side of the slotted plate o¹⁰ and these slides are retracted by a bow or other spring U as in said prior patent. The outer ends of the slides R R are provided with rollers r² r² on their outer 75 ends and these roller-carrying outer ends are projected beyond the side edges of the slotted plate o¹⁰ so as to overlie the cams M⁵ when the hand lever t' is thrown to the rear, at which time the hand lever will enter the 80 first notch o¹⁸ of latch o¹⁰ and hold the hand lever in this position. The two slides R R are provided with two friction catches or grips R' R' formed of bent springs, one end r⁵ of each of which is fixedly connected to 85 the slide, while the other or working end r⁶ lies next to an opening o²⁰; one such opening being formed in plate o¹¹ adjacent to each roller r². When the legs p p of clamp P before referred to are passed down 90 through the openings o²⁰ they will first engage the extensions E⁶ E⁶ of latches E⁵ E⁵ and throw the latches over the pin-carrying bases or bars J' and then lie in front of said extensions E⁶ to hold the latches in place, as 95 before described, and said legs p p will then lie next to the outer biting ends of the friction catches or grips R' R', so that after the slides R R are forced outwardly over cams M⁵ the catches or grips R' will, by a further 100 movement of hand lever t', be forced into biting or gripping contact with the legs p p of sheet clamp P. The hand lever t' will now enter the notch o¹⁷ in the latch O¹⁰. A laterally extending hook t¹⁰ on hand lever t' 105 extends over the free inner curved end of latch O¹⁰ so that the latch and lever will be held from disengagement when the sections O' O² are unlatched and moved to withdraw the slotted plate o¹⁰ from the pins J.

The clamp P comprises a crossbar bent up at the middle to form a handle p² and bent down at its ends to form the legs p p. Upon the crossbar is secured the clamping bar p³ formed of channel iron, as shown.

The sets of pins J may be interchanged at any time by first moving the carrier O to the right from over the base J'.

In returning the carrier to its position over the base J' its slotted end will engage the latches E⁵ E⁵ and push them back from over the ends of base J'. The set of pins now in place will be held there by the carrier during the filing of the sheets on the pins. When the pile is completed the legs of the clamp will be inserted in the openings o²⁰ as above described and the clamp forced down during which operation the legs p p will engage the latch extensions E⁶ and force the latches E⁵ E⁵ over the 130

base of the pins to hold them down on the axle against the upward lifting movement of the carrier in removing the completed pile from the pins.

5 The legs p will pass the extensions E^6 and lie in front of them so that the latches cannot swing back off of the bar J in the further operations.

To hold the pile of clamped sheets against the upward compressing movement of the carrier O hooked arms X are provided to hook over the clamp P when it is applied. These hooked arms X extend up from a crank shaft X' mounted in eye bolts

15 x^2 extending from the inner side of the lower end of vertical plate F' and into the axle E below the lower edge of the pin base J' , so as to permit the removal of the pin carrying base from the upper angular side 20 of the axle. The shaft X' has a depending operating arm x connected by a horizontal link x' with a middle eccentric w^3 on a transverse rock shaft W' mounted in the side bars A' under the free inner end of 25 carrier O . The rock shaft W' is provided with an operating handle w^2 and when this handle is thrown to the right the hooked arms X will be thrown over the clamp P , and vice versa.

30 The rock shaft W' is further provided adjacent to its ends with other cams or eccentrics $w' w'$ over which extend the two pawls W . These pawls W are thrown into contact with two curved ratchets $m^{19} m^{19}$ on the hubs m^5 of levers M by springs $w w$, and the pawls W are raised from contact with the ratchets after the hooks X have been withdrawn, by moving the handle w^2 farther to the left.

40 That is, the first movement of crank w^2 to the left causes cam or eccentric w^3 to withdraw the hooks X from over the clamp

P , or a pile of sheets, and a further movement causes the cams or eccentrics $w' w'$ to lift the pawls W .

The cam or eccentric w^3 will in its extremes of movement pass the center and so lock the parts against accidental movement.

Binding sleeves Y may be placed on the 50 pins J , and the lower ends of these sleeves have outwardly extending flanges y , on which the lower cover or back rests. These sleeves may be of a length to inclose the pins throughout their entire length and 55 their upper ends may be pinched and bent out over the upper or outer cover to hold the leaves in bound or book form. Or where a thinner book is to be formed shorter sleeves may be used. Or a sleeve

60 may be formed of a shorter section Y' to extend partially through the pile and a solid pin Y^2 may be driven through the outer portion of the pile until its inner pointed end y^3 enters and expands the tu-

bular member and its head y^4 rests on top 65 of the outer cover.

A sheet-receiving box C substantially like that in my said patent is provided, but it has at the lower end of its converging sides a bracket C' having a member c secured to the back of the box, a member c' extending forwardly under the lower meeting ends of the converging sides of the box and a depending Y -shaped member c^2 having a recess c^3 which receives the headed end e of axle E , while the Y -shaped member engages the outer face of the side bar A' of the base.

A sliding gage Q is mounted at one end of the gage flange g^2 for the sides of the 80 sheets to rest against and this gage is actuated along the gage flange g^2 and sheet guide F by means of a lever Q' pivoted to the under side of the gage flange g^2 and connected by a link q with said sliding 85 gage Q .

A brief description of the operation is as follows: The sheets are placed against guide F with their lower edges on gage plate g^2 , and the lever arms M are pressed down to 90 cause the punches to perforate the sheets. The lever arms M will now be raised and thrown over to the right until the punches carrying the sheets are in vertical alinement with the filing pins J . Then the 95 lever arms are pressed down to cause the stripper L to force the punched sheets down on the said pins J . This set of pins may be removed, as before described, if a set of different sized sheets are to be filed or if 100 there are enough of the size already being filed to form a book the punching and filing go on till a book is formed, when the top cover may be applied. It is understood that the other cover was applied in the beginning.

In pressing the lever arms M down in their stripper actuating movement the cams $M^5 M^5$ will have passed low enough to permit the lever t' to throw the rollers 110 $r^2 r^2$ outward over the upper sides of said cams.

The lever will now enter the first notch o^{18} of the latch O^{19} .

The clamp P will now be placed over the 115 pile of sheets and its legs p forced down through the openings o^{20} , where they throw and lock the latches E^5 , as before described. The crank handle w^2 will now be moved to the right to lower the pawls W and 120 throw the hooks X over the clamp to lock it against upward movement with the carrier O .

The crosshead K will now be moved from over the pins J and the lever arms M will also be swung to the left and in so doing the cams M^5 will engage the rollers r^2 and the links o^9 will pull on angle lever o^7 and so

the carrier will be raised bodily and vertically and the pile of sheets compressed between the carrier and the hooks X X. The pawls W W and ratchets will hold the parts 5 as the pressure is applied. When sufficiently compressed the lever t' is thrown over and enters the second notch o¹⁷ and in so doing the grips R' R' will be thrown out against the clamp legs p and lock the clamp P to the 10 carrier O.

The crank handle w² may now be swung to the left to retract the hooks X X and lift the pawls W, whereupon the lever arms M M may be swung to the left with the punching 15 carrying devices till their normal punching position is reached.

The sheet and clamp carrier may now be swung up to the vertical position by means of handle O⁷ until arrested by a stop a¹⁹ 20 on the end piece A², thus drawing the sheets off of the pins.

The book may be released when sewed or riveted by retracting the lever t' to its normal position so as to release the legs of the 25 clamp P from the friction catches or grips.

To glue a cover over the stitches or clenched ends of the sleeves or tubes remove the set of pins J, place the book against the vertical wall F', apply the glue and the 30 cover, place a small board under the hooks X X, then operate lever arms M M to lift the carrier O and force the book upward against the hooks. Let the book remain till the glue dries and then remove.

35 I have shown a book the leaves of which are secured by the two forms of tubes or sleeves and also by stitches.

The leaves by my improved apparatus may be filed or bound in all sizes of books 40 day by day instead of piling the leaves into boxes and letting them remain till the end of a month before making them into a book or books. It follows that the sheets may be filed while new and they will remain intact 45 from their first handling so that ready reference may be had to them.

It is little or no trouble to interchange different sets of pins for different sizes of sheets or leaves.

50 Then by having the binding sleeves in place on the pins the leaves may be readily bound, as before described.

The apparatus may be made up within a suitable office cabinet or other piece of furniture.

What I claim is:

1. In a loose leaf binding machine, the combination with a plurality of receiving pins, of a bodily movable set of punches, a 55 normally retracted stripper carried thereby; said punches being movable from the punching position into alinement with said pins, means for actuating the punches, and a connection between said punch actuating means and the stripper for actuating the latter to

force the sheets from the punches to the pins.

2. In a loose leaf binding machine, the combination with a punching mechanism adapted to carry the sheets or leaves from the punching position to the filing position, of interchangeable sets of receiving or filing pins to receive punched sheets of varying width from the punches. 70

2. In a loose leaf binding machine, the combination with a removable set of receiving or filing pins and a support therefor, of a bodily movable set of punches, a normally retracted stripper carried thereby; said punches being movable from the punching position into alinement with said pins, means for actuating the punches, and a connection between said punch-actuating means and the stripper for actuating the latter to force the sheets from the punches to the pins. 80

4. In a loose leaf binding machine, the combination with a crosshead provided with punches, swinging guide rods upon which the crosshead slides, an operating lever, links connecting the lever and crosshead, and an anvil to coöperate with the punches, of a plurality of receiving pins over which the crosshead may be swung to bring the punches into alinement therewith, a stripper on the crosshead, and operative connections between the stripper and the operating lever whereby a further movement of the lever will cause the stripper to transfer the leaves from the punches to the pins. 95

5. In a loose leaf binding machine, the combination with a crosshead provided with punches, swinging guide rods upon which the crosshead slides, an operating lever, links connecting the lever and crosshead, and an anvil to coöperate with the punches, of a plurality of receiving pins over which the crosshead may be swung to bring the punches into alinement therewith, a spring retracted stripper on the crosshead and provided with end arms alongside the guide rods; the lower ends of said arms having lateral extensions in the path of the said lever arms for the purpose described. 100

6. The combination with a crosshead provided with punches, swinging guide rods upon which the crosshead slides, an operating lever, links connecting the lever and crosshead, and an anvil to coöperate with the punches, of a plurality of receiving pins over which the crosshead may be swung to bring the punches into alinement therewith, a spring retracted stripper on the crosshead and provided with end arms alongside the guide rods, lateral extensions at the lower ends of the arms in the path of said lever, and a roller guide also on each of the said arms and engaging the swinging guide arms. 110

7. In a loose leaf binding machine, the combination with a tubular anvil having punch-receiving openings therethrough and 130

provided with an endwise removable drawer to receive the punchings, and a housing in which the anvil is mounted, of a plurality of punches coöperating with the anvil, means for operating the punches, and a series of vertically disposed receiving pins over which the punches may be swung into alignment therewith.

8. In a loose leaf binding machine, the combination with a removable set of receiving pins having a base and a support therefor for the punched sheets, of a sheet carrier having a slotted inner end movable longitudinally across the base of the set of receiving pins to permit of the removal and insertion of sets of pins.

9. In a loose leaf binding machine, the combination with a removable set of receiving pins having a base and a support therefor, and means for locking the set in place, of a sheet carrier having a slotted inner end to overlie the base of the set of pins, and a sheet clamp having legs extending through said slotted end and controlling said locking means.

10. In a loose leaf binding machine, the combination with a removable set of receiving pins having a base, a cross axle on which the set of pins rests, latch hooks pivoted on the axle to swing over the upper side of the base of the set of pins; said hooks having lower extensions, of a sheet carrier movable at its inner end across the base of the set of pins to release the hooked latches, and a clamp having legs extending through the said sheet carrier to engage the latch extensions as described.

11. In a loose leaf binding machine, the combination with a removable set of receiving pins, a cross axle having apertures in which rest the lower projecting ends of the pins, and latches holding the set of pins on the axle, of a sectional hinged sheet and clamp carrier controlling the pins and their latches, substantially as described.

12. In a loose leaf binding machine, the combination with a plurality of vertically disposed sheet-receiving pins, a punching mechanism at one side of the pins including a sliding crosshead provided with punches, a cross axle below the pins, guide rods for the crosshead journaled on said axle, lever arms also journaled on the axle and operatively connected with the crosshead; said crosshead being movable over the pins with the punches in line therewith, of a vertically swinging sheet carrier extending at its free end across the lower end of the set of pins to underlie the pile of sheets, a removable clamp at the inner end of said carrier having legs extending therethrough, cams on the hubs of the lever arms, slides on the inner end of the carrier adapted to be thrown outwardly across the upper sides of said cams for lifting the carrier, and means

to engage the upper end of the clamp to prevent its upward movement while the cams are lifting the carrier to compress the pile of sheets, and means actuated by said slides to lock the clamp to the carrier and hold the compressed pile of sheets while the carrier is moved upwardly.

13. In a loose leaf binding machine of the character described, the combination with the sheet and clamp carrier having a slotted inner free end, apertured at opposite sides, and a removable clamp having legs extending down through said apertures, of transverse slides on said carrier, a longitudinal rock shaft having a head at one end between said slides for forcing them apart to project their ends beyond the carrier, spring grips carried at one end by said slides with their free ends adjacent to the said apertures to grip the clamp legs, a hand lever for rocking said shaft, and lifting means to engage the outer ends of said slides when projected, for the purpose described.

14. In a loose leaf binding machine of the character described, the combination with the sheet and clamp carrier having a slotted inner free end apertured at opposite sides, and a removable clamp having legs extending down through said apertures, of transverse slides on said carrier, a longitudinal rock shaft having a head between the abutting ends of said slides for forcing them apart, to project their ends beyond the carrier, spring grips secured at one end to the slides with their free ends adapted to grip the clamp legs, a hand lever for rocking said shaft, and a latch having notches for locking said lever in its first movement of projecting the slides and in its further movement of causing the grips to firmly bite the legs of the clamp.

15. In a loose leaf binding machine of the character described, the combination with a support and a set of filing pins provided with a base removably engaging said support, of the sheet and clamp carrier formed in two hinged sections, and having a slotted inner end to overlie the base of said pins and provided with vertical apertures, a removable clamp having legs extending through said apertures, slides mounted on said carrier adjacent to said slotted end, spring grips mounted at one end on the slides and adapted at their free outer ends to grip the clamp legs, a longitudinal rock shaft on said carrier having a head between the adjacent ends of the slides to project them outwardly, for the purpose described, a hand lever extending from the rock shaft upwardly between the two sections of said carrier, a latch to lock the two carrier sections together and having a notched extension to engage and lock said hand lever, as described.

16. The combination in a loose leaf bind-

ing machine of the character described with the vertically disposed pins having a base, the punching and stripping mechanisms and operating lever arms therefor provided with 5 cams, of a sheet and clamp carrier having transverse slides at its inner end which overlie the base of the pins, means for projecting the slides outwardly across said cams, a vertically movable slide to which the outer end 10 of the carrier is pivoted to swing vertically, cam levers engaging said slide, and links connecting these last named levers with the first named main operating levers so that both ends of the carrier will be simultaneously raised, for the purpose described.

17. The combination with the sheet punching and transferring mechanism, and a curved sheet guide having a vertically disposed inner wall, a support, and a vertically 20 disposed set of pins adjacent to said vertical wall to receive the sheets from the punching and transferring mechanism, said pins having a base removably engaging said support, of a vertically movable sheet carrier overlying at its inner end the base of the pins, hooked arms mounted at the inner side of 25 said wall and adapted to be projected outwardly through the upper end thereof to prevent upward movement of a pile of sheets resting on said sheet carrier, means for actuating said hooked arms, and means for raising and lowering the sheet carrier from and to the punching mechanism.

18. In a loose leaf binding machine, the 35 combination with the punching and transferring mechanism, lever arms for actuating the same; the hubs of the levers having cams and ratchets thereon, and vertically disposed pins to which said punching and transfer-

ring mechanism transfers the sheets, said pins having a base, a transverse rock shaft having upwardly extending hooked arms to overlie a pile of sheets on said pins, pawls engaging said ratchets to hold said levers against movement in one direction, a cam 40 shaft having an intermediate eccentric, a link connecting said eccentric to the said transverse rock shaft, and end eccentrics on said shaft engaging the said pawls to lift them from the said ratchets, an upwardly 45 movable sheet and clamp carrier having a slotted inner end overlying the base of the set of pins, a removable sheet clamp adjacent said slotted inner end, and means for actuating the carrier from the said cams on 50 the lever arms.

19. In a loose leaf binding machine, the combination with a plurality of receiving pins and flanged sleeves mounted removably on the pins and inclosing same from their 55 upper ends downwardly, of a punching and transferring mechanism to punch the sheets and transfer them to the said sleeves; the upper ends of the sleeves being adapted to be bent laterally to form upper retaining 60 flanges or tongues.

20. In a loose leaf binding machine of the character described, the combination with the punching and transferring mechanism, the transverse axle serving as the axis thereof and provided with an outer headed end and the receiving pins to which the punched sheets are transferred, of a triangular sheet-receiving box having at its lower end a slotted bracket fitting over the headed end of 70 the axle, as described.

In testimony whereof I affix my signature.

HENRY M. CRIPPEN.
